United States Patent Office

Des. 194,490
Patented Jan. 29, 1963

194,490

MOTOR GENERATOR UNIT

Roger C. Winslow, Pound Ridge, N.Y., and Albert S. Bloom, Stamford, Conn., assignors to Consolidated Diesel Electric Corporation, Stamford, Conn., a corporation of New York

Filed Oct. 24, 1961, Ser. No. 67,242

Term of patent 14 years

(Cl. D77—1)

Fig. 1.

Fig. 2.

Fig. 3.

Fig. 4.

Fig. 5.

FIG. 1 is a front elevational view of a motor generator unit, showing our new design;

FIG. 2 is a left side elevational view;

FIG. 3 is a right side elevational view;

FIG. 4 is a rear elevational view; and

FIG. 5 is a top plan view thereof.

We claim:

The ornamental design for a motor generator unit, substantially as shown.
